Bridge Beach Co.

Design for Water and Ware
Patented Aug 9 1859

Fig 1

PATENTED 1859

BRIDGE BEACH CO. ST. LOUIS

EDGE PAINTER NO 2

Des. 1131

Isaac Dezonche, of St. Louis, Mo.
Letters Patent No. 1131. Oct. 12, 1859.

The schedule referred to in these Letters Patent and making part of the same.

To all whom it may concern:

Be it known that I, Isaac de Zonche, of the City and County of St. Louis and State of Missouri, have invented or produced, a new and original design for the plates and doors of a Parlor Coal Stove, and I do hereby declare that the said Stove plates and doors are clearly represented by the accompanying drawings:

Fig. 1. is a view of the front plates and doors of my ornamental Coal Stove;

Fig. 2. a view of its rear plate:

Fig. 3. a view of its side plates.

Fig. 4. a perspective view of said Stove: and

Fig. 5. a vertical section, showing the curved and angular shape of the respective plates and doors in the above mentioned Stove, and the relative positions of the same when they are united to each other.

A, and B, indicate the upper and lower front plates of my ornamental parlor-stove. C, and D, indicate the upper and lower side plates of the same; B, the back plate, and F, a centrally perforated plate which is inserted between the upper and lower series of plates in said Stove.

The fire-doors a, a, are combined with and cover an opening in the upper portion of the plate B; the damper doors b, b, are combined with and cover an opening in the lower portion of said plate; and the letters g, g, on the plate B, are intended to indicate the positions of ornamentally shaped apertures in said plate.

The relief figures which ornament the aforesaid Stove-plates and doors, are pictorially represented with such a degree of clearness in the accompanying drawings, that a written description of each of said figures is not deemed necessary.

What I claim as my invention and desire to secure by Letters Patent, is the ornamental shape and configuration of the Stove-plates and doors represented in the accompanying drawings.

The above specifications of my design for a Parlor Coal Stove signed and witnessed this ___ day of July 1859.

Witnesses
